2,007,544

PRODUCTION OF PERFORATED WEBS

Otto C. F. Meisel, Milton, Mass., assignor to Meisel
Press Manufacturing Company, Boston, Mass.,
a corporation of Massachusetts

Application May 4, 1934, Serial No. 723,856

4 Claims. (Cl. 101—226)

This invention relates to the perforation of paper and the like whereby a sheet or strip is produced adapted ultimately to be torn along lines of weakness to produce small sections, as, 5 to cite a familiar example, a sheet or strip of postage stamps, although the strip or sheet may not be printed, and the object is to provide a method of operation and a novel form of perforated web facilitating the production of such 10 strips or sheets in a form permitting ready detachment of the sections as required.

My invention will be well understood by reference to the following description taken in connection with the accompanying drawing, where- 15 in:

Fig. 1 is a broken plan view of a novel form of web having a number of duplicate impressions thereon separated by transverse lines of weakness;

Fig. 2 is a diagrammatic side elevation of a printing press mechanism adapted to be used in the production of the article; and

Fig. 3 is a front elevation of a perforating head shown in Fig. 2.

At the present time sheets or strips of forms, labels, stamps or the like are frequently produced on a web printing press, the printed sections being arranged in transverse and longitudinal rows in such number as the size of the 20 work permits. Perforating attachments, usually embodied as a part of the press mechanism, provide lines of transverse weakness extending across the web between the transverse rows. Longitudinal lines of weakness may be provided between 25 the longitudinal rows, or, if the product is to be packaged in strip form, the web is slit between the longitudinal rows. The web, slit or perforated, is finally rewound or otherwise disposed of. In handling the web after perforation 30 difficulties occur because of breakage along the transverse lines of weakness. This is in part avoided by leaving large ties. That is, the perforations are relatively widely spaced, leaving a considerable proportion of the length of the line 35 uncut to bind together the adjacent sections. Obviously, however, it is then less easy to separate the sections when they are to be detached one from another in their ultimate application. Under my invention such breakage is avoided while 40 a clean line of perforation is provided along which the sections may readily be separated. If the material is to be printed, no additional difficulties are encountered.

Referring to Fig. 1, I have there shown a web 45 of paper which is ultimately to be divided into

a number of small sections of restricted width as compared with the width of the web. These sections 7 are herein identified by the X or St. Andrew's cross thereon, which might be considered as a diagrammatic showing of some printed inscription. The sections 7 are arranged in longitudinal series but the elements of adjacent series are offset. Herein the end of alternate longitudinal rows are disposed in alignment and between the ends of the intervening longitudinal 10 rows. Otherwise expressed, the areas are arranged in staggered relation. Transverse lines of perforation 9 are provided between the sections and these perforations, corresponding to the ends of the sections, are likewise staggered, as 15 clearly seen from Fig. 1, so that there is no continuous line of perforation across the web. The web 5, considered as a whole, therefore, has no markedly weak point therein and can withstand considerable traction, and in general after perforation may be handled in substantially the same manner as an unbroken, unperforated web. Longitudinal lines of perforation between the longitudinal rows of sections 7 may be provided in the usual manner or, if the product desired is 20 a series of sections in strip form, the web may be slit between the longitudinal rows. When so slit, each strip, of course, has lines of weakness extending completely across the same, but as the web consisting of a number of these strips 30 may be handled as a unit for rewinding or the like, the weakened lines are offset and the benefits of retained strength are still advantageously realized.

Referring to Fig. 2, I have there shown in diagrammatic form a method of production in which the web 5 is drawn from a supply roll 11, through feed rolls 13, passes through a printing couple 15, and then is operated on by a perforating mechanism 17, which may be advantageously of the type described in the application of Charles A. Meisel, Serial No. 691,189, filed Sept. 27, 1933, which mechanism forms the transverse lines of perforation 9. The longitudinal rows of impressions or sections may be separated from one 45 another by a suitable slitting mechanism 19 and the slit web forwarded by feed rolls 21 to suitable rewinding mechanism forming the rewound roll 23.

The perforating mechanism 17 here shown comprises a fixed knife 25 having a serrated edge presented beneath the web 5 with which cooperate knives 27 on a rotary head 29, the knives in the rotation of the head making contact with the web 5 at suitable intervals to cut transversely 50

55

extending perforations therein. As seen in Fig. 3, at least the edges of knives 27 are discontinuous to form transversely spaced edge portions to cooperate with the fixed blade of knife 25 to form spaced lines of weakness, for example, along alternate longitudinal rows of the sections 7. Thus, in Fig. 3 the edge of the knife is ground back at 31, leaving the true edges 33 corresponding to the length of the transverse lines of perforations 10 which it is desired to form, the intervening spaces corresponding to the ground-back portions 31 corresponding to the intervening sections which it is not desired to perforate at that location. The succeeding knife has its active edge portions 31 arranged in staggered relation to those of the preceding one, their position being in alignment with the gaps 31 of the preceding knife. Obviously the arrangement of cutting edges among the several knives may be widely varied as conditions require.

A finely cut and efficient line of perforation may be provided without danger of breakage during production.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A paper web presenting a series of longitudinal zones each divided into sections by lines of weakening, the lines of adjacent zones being relatively displaced one from another. 5

2. The method of preparing strips having transverse lines of weakening dividing them into sections which comprises operating on a web of a width to provide a plurality of strips, forming spaced lines of weakness in longitudinal zones of 10 the web, the lines in adjacent zones being relatively displaced one to another and longitudinally dividing the web to form the strips.

3. The method of producing small printed sheets which comprises feeding a relatively wide web, 15 printing longitudinal series of inscriptions thereon, the impressions of adjacent series being relatively offset, separating the successive imprints of a series by lines of perforation, then providing division lines between the series and rewinding the 20 web.

4. The method of providing strips of small sheets connected along perforated lines which comprises feeding a relatively wide web, cutting longitudinal series of spaced lines of perforation 25 therein, the lines of adjacent series being relatively offset, slitting the web to form strips and rewinding the so longitudinally divided web.

OTTO C. F. MEISEL. 30
